UNITED STATES PATENT OFFICE.

CHARLES M. DAVIS, OF CHICAGO, ILLINOIS.

TELEGRAPHIC APPARATUS.

SPECIFICATION forming part of Letters Patent No. 707,557, dated August 26, 1902.

Application filed July 27, 1901. Serial No. 69,999. (No model.)

To all whom it may concern:

Be it known that I, CHARLES M. DAVIS, a citizen of the United States, residing at Chicago, in the county of Cook and State of Illinois, have invented a new and useful Improvement in Telegraphic Apparatus, of which the following is a specification.

This invention relates to telegraphic apparatus.

10 The object of the invention is to provide means whereby the effects of leakage or escape along the line due to sleet, snow, rain, or the like may be avoided.

15 Other objects of the invention will appear more fully hereinafter.

The invention consists substantially in the construction, combination, location, and arrangement of parts, all as will be more fully hereinafter set forth, as shown in the accompanying drawings, and finally pointed out in the appended claims.

20 Referring to the accompanying drawings and to the various views and reference-signs appearing thereon, Figure 1 is a diagram of a telegraph-line connecting two terminal stations, with intermediate stations indicated, and over the entire course of which line a storm is supposed to be prevailing. Fig. 2 is a view in diagram illustrating an arrangement embodying the principles of my invention and showing the relation thereof to the line-wire. Figs. 3, 4, and 6 are diagrams illustrating various modifications in the arrangement of the parts. Fig. 5 is a diagram

30 illustrating shunts in the main-line circuit.

35 The same part is designated by the same reference sign wherever it occurs throughout the several views.

When a rain, snow, or sleet storm is in progress over any part of the course of a telegraph-line, the working of the line is interfered with and the transmission of messages thereover is impaired or rendered difficult. This is due to the fact that the rain, snow, 40 sleet, or the like forms a conducting path to the earth, termed a "leak" or "escape," and when in transmitting a message a key is opened at an office which is located between a point where a leak or escape occurs and one terminal of the line at which is located the main battery the current through the path afforded

by the leak or escape continues to magnetize the cores of the magnets of all or some of the receiving instruments or relays located between the point of leak or escape and the 55 main battery at the other terminal of the line to a degree sufficient to prevent their levers from falling away or being retracted or withdrawn from their closed or attracted position. While the levers remain thus attracted the 60 operators at such offices hear no sound from their instruments even though their stations may be called by the operator at some other station located on the other side of the escape, and hence no response is made to such calls, 65 while the operator at such other station may continue to fruitlessly call. This results in waste of time and great delay to the transmission of messages. It also frequently happens that where an office on one side of the 70 point where occurs an escape or a leak has heard the call of an office on the other side of it and replied to it and is in course of exchanging communication such communication is interrupted by the "breaking in" of 75 some other office, where the relay-lever does not respond to the signaling that is passing over the line in an effort to use the line, the operator attempting to use the line being ignorant of the fact that the line is already 80 in use because his instrument does not respond or give indication of the passing of a message over the line. When a leak or escape is present throughout the entire length of the line, as would be the case should a 85 rain, sleet, or snow storm be in progress over its entire length, the impairment of the usefulness of the line is increased, and it is frequently rendered wholly or almost wholly 90 useless.

The special object of the present invention is to render the working of a line practically as good during the prevalence of a rain, sleet, or snow storm or the like as in clear weather, whether a storm prevails over a portion of 95 the length of the line or over its entire length, and I accomplish the desired object by making provision for the momentary opening of the line-circuit by disconnecting it from its main battery or batteries directly after the 100 opening of a transmitting-key, thereby withdrawing all current from the line, and hence

causing the relay-lever magnets to become de-energized and said levers to fall back or to be retracted.

Referring to the diagram in Fig. 1, reference-signs R and H designate terminal offices at which are located main batteries MB and MB', said batteries being connected to earth E in the usual manner. L designates the line-wire. B, C, D, F, and G designate local stations intermediate the terminal stations R and H, and the slanting lines B' indicate a snow, rain, or sleet storm prevailing throughout the entire length of the line.

Referring to the diagram in Fig. 2, I have shown one construction and arrangement embodying my invention and wherein reference-sign R' designates a relay, which may be of the usual construction and located in the circuit of the main line L. K designates a key of the usual construction also in said main-line circuit. M designates what I shall term the "line-adjuster." This line-adjuster may assume many different forms in the specific details of construction and arrangement thereof. As shown in Fig. 2, it comprises two coils ac and rc, arranged to effect the operation of a lever l. Said lever is pivotally mounted and operates between the limiting-stops c and b, the coil ac operating when energized to attract lever l and to hold the same against its front limiting-stop b, while the coil rc operates on said lever to retract the same from its front limiting-stop b and to hold the same against its rear limiting-stop c. As shown, the coil ac is located on one side of the pivot of lever l, while the coil rc is arranged on the opposite side of the pivot of said lever. It is obvious, however, that this specific arrangement is immaterial, and said coils may be arranged on opposite sides of the lever l, on the same side of the pivot thereof, as indicated in Fig. 6. The coils ac and rc are so relatively constructed and arranged that the magnetic effect of coil ac or the attractive power thereof upon lever l is greater than the attractive power exerted upon said lever by coil rc, so that except when the circuit through coil ac is open said coil overcomes the effect of retracting coil rc and attracts lever l against its front limiting-stop b. Arranged in the circuit of coil ac are resistances r r', as will presently be explained, and similarly in the circuit of coil rc is a resistance r'', and hence the current in the circuits of said coils may be regulated in strength by varying said resistances. It is obvious that the effect exerted by the coils ac and rc upon lever l may also be regulated by adjusting said coils closer to or farther away from said lever. The lever l forms part of the main-line circuit and operates to break or open said main-line circuit whenever said lever leaves contact with its front limiting-stop b. S_w designates a switch included in a shunt-circuit of the main line around lever l, and when said switch is closed upon the contact z the main-line circuit is shunted around said lever. Reference sign

S designates a sounder having an armature-lever l', said lever playing between the limiting-stops d d', and said sounder may be of the usual construction and arrangement, except that the lever l' serves to make and break an electric circuit at its back stop d. Lb designates a source of local current-supply—such, for instance, as a battery of primary cells, a dynamo, or other convenient source of electromotive force. Reference sign l² designates the armature-lever of relay R', this lever playing between the limiting-stops i and h. When the lever of relay R is closed against its front stop h—that is, when sufficient current is traversing the main line L, in which line the coils of relay R' are included—the path of the local circuit is traced as follows: from one pole of local battery Lb through conductor f, conductor g, lever l², stop h to point j, where the circuit divides, one branch of which may be designated the "sounder branch," passing through the coils of sounder S and conductor k to the point o, and the other branch, which may be called the "line-adjuster" branch, continues from point j through conductor m, resistance r, conductor n, the windings of coil ac, conductor t to point o, where it unites with the sounder branch, and thence returns by a conductor e to the other pole of the local battery Lb. Thus the total local current divides between the two branches when lever l² is in its closed position against its front stop h, thereby effecting an attraction of sounder-lever l' against its front limiting-stop d', at the same time effecting an attraction of the line-adjuster lever l to its front limiting-stop b.

In the foregoing description and in the arrangement of parts as shown in Fig. 2 I have assumed that the transmitting-key at a distant transmitting-station has been closed, so as to close the circuit of the main line L. When the key and circuit are open at the distant transmitting-station, the relay R' at the receiving-station is sufficiently de-energized to cause its lever l² to be retracted under the influence of its retracting-spring rs, thereby leaving the front contact or limiting stop h and being drawn back against its back stop i. In beginning its movement toward an open position against its back stop i said lever opens the local circuit in both the sounder branch and the line-adjuster branch, and hence the line-adjuster lever l, responding to the influence of its retracting-coil rc, which is energized by current from the local battery Lb, through the path of conductor u, resistance r'', the windings of magnet-coil rc, conductor v, and conductor e to battery leaves its front contact b and is retracted toward its back stop c, thereby breaking at lever l the main-line circuit. At this moment it will be seen that the main-line circuit is open at the distant transmitting-station—say, for instance, the terminal station H (assuming that the message transmitted is proceeding from said station)—and also at the line-adjuster lever l

at the local or receiving station—say, for instance, at the terminal R, as seen in Fig. 1. Consequently as connection from the main line is broken to both main batteries all current is withdrawn from the line, and consequently the relay-levers at all the intermediate offices or stations are relieved of any attractive force exerted thereon by their magnets and yield to the force of their retracting-springs, and hence are caused to fall back to their open position, thereby operating their respective sounders. The main-line circuit remains open, however, at line-adjuster lever l only momentarily, for as soon as lever l' of sounder S is moved by its retracting spring w into contact with its back stop d it closes the local circuit from local battery Lb as follows: through conductor f , resistance r' , lever l' , stop d , conductor g , conductor n , attracting coils ac of line-adjuster M, conductor t , conductor e to the opposite pole of battery Lb , thereby causing line-adjuster lever l to be again attracted to its closed position in contact with its front limiting-stop b , and hence closing the main-line circuit at that point. The connection of sounder-lever l' with its back stop d also closes the local circuit in the sounder branch, as follows: From local battery Lb , through conductor f , resistance r' , lever l' , stop d , conductor g to point p , thence through resistance r , conductor m , sounder S, conductor k to point o , and thence returning to the other pole of the local battery through conductor e ; but it will be seen that this circuit includes the resistance r , which is not included in the line-adjuster branch, said resistance being now transferred from the line-adjuster branch to the sounder branch, and hence the current traversing the circuit last above traced is too weak to magnetize the core of sounder S sufficiently to attract lever l' away from its back stop d . The resistance r' should be so adjusted as to cause the current which flows through line-adjuster coil ac to be of about the same strength as it was at first or somewhat weaker, provided it be sufficient to promptly overcome the retraction exerted by the retracting-coil rc of the line-adjuster M upon lever l . Under these conditions in continuing the transmission from the distant station—as II, for instance—when the key at the transmitting-station is again closed the full flow of current is returned to the main line and the relay-levers at all the offices are attracted into their closed positions, thereby operating their respective sounders, and when lever l' resumes its closed position against its front limiting-stop h , in consequence of the closing of the key at the transmitting-station, the resistances r and r' are momentarily shunted and the resistance r is removed from the sounder branch, thereby strengthening the current in that branch sufficiently to cause lever l' to be attracted to its closed position against its front stop d' , thereby breaking the circuit through the back stop d . The breaking of this circuit,

however, does not cause any movement of the line-adjuster lever l , because the circuit through its attracting-coil ac is maintained by the contact between relay-lever l^2 and its front contact or stop h , and said line-adjuster lever l remains against its front stop b until contact between relay-lever l^2 and its front stop h is again broken. Thus it will be seen that when the transmitting-key at the distant station—as H, for instance—is opened and the line-circuit is also opened at the line-adjuster lever l , the relay-levers at all offices intermediate said adjuster-lever l and the distant station at which the key has been opened will fall back because of the withdrawal of all current from the line. As soon, however, as the line closes at the adjuster-lever l the current caused by the main battery MB, through the leak or escape, returns to the line; but it does not follow that the relay-levers will now return to their closed position on account of this escape or leak of the current, because being in their open position they are farther removed from the relay-cores than before the key at the distant transmitting-station was opened. In other words, the opening of the key at the distant transmitting-station and the momentary opening of the line-circuit at the adjuster-lever l and withdrawing all current from the line permitted the relay-levers to be fully retracted from their actuating-magnets; but when said magnets are again partially energized by closing the line-circuit at the adjuster-lever l , and the consequent flow of current from the main battery MB through the leak or escape, the core magnetism will not be sufficient to attract said relay-levers away from their open position, and they will not be again attracted to closed position until the key at the distant transmitting-station is again closed. In other words, the flow of current through the line due to the leak or escape and through the path offered by the rain, sleet, or snow storm is not of sufficient strength to energize the relay-magnets of the intervening stations sufficiently to attract the relay-levers from their fully retracted or open position.

I have described the arrangement as applied at one terminal station, as R, in receiving messages transmitted from another or distant terminal station, as II. Of course it will be understood that a similar arrangement of apparatus embodying my invention should be located also at the other terminal station, and the same operation as that above described will be obtained in such case when messages are transmitted from either terminal station or from or to any other station at which the apparatus may be located, and the apparatus may also with even greater advantage be located at any or all intermediate stations or where there is no central or main battery. On very long lines or where the line is poorly insulated and the leakage or escape is exceptionally great the location of the apparatus

embodying my invention at one or more intermediate or centrally-located offices between the main terminals will be found of advantage. The relay-lever at such an intermediate office will almost invariably be adjusted to respond to transmission from either terminal, even at times when on such line the receiving instrument at one terminal station may not be adjusted to respond to transmission of messages from the other terminal, and also the receiving instrument at both terminals will almost invariably be adjusted to respond to the transmission of signals or messages from the centrally-located or intermediate office or offices, and thus the line-adjusting mechanism embodying my invention, located at a central or intermediate station, will be operated by the transmission of a signal or message from one of the terminals and will operate to repeat the transmitted signal or message to the receiving apparatus at the other terminal. The greatest possible benefit to be derived from the use of my invention is obtained by having an apparatus embodying my invention located at every office on the line, for the reason that the escape or leak is seldom or never so great that a relay-lever at any particular office or station will not respond to the opening of the line at the next adjacent office or station. Consequently with an apparatus embodying my invention located at every station on the line the line would open momentarily at every office directly after the opening of the transmitting key at any point on the line, and hence the working of the line would be as free and clear as though there were no escape or leak on it. If the leak or escape is so great that the relay-lever at any particular office will not respond to the opening of the line at the office next adjacent to it, then such leak or escape is properly termed a "ground" and requires other means for obviating the effect of the same.

In the modification shown in Fig. 3 the retracting-coil rc is omitted and the function thereof is performed by a retracting-spring y . The operation of this form of my device is similar to that above described with reference to Fig. 2 and is as follows: In the closed position of relay-lever l^2 the local current flows from one side of the local battery Lb , through conductor f , conductor g , relay-lever l^2 , front limiting-stop h , the coils of sounder S , conductor k , conductor n , the coils of magnet ac of the line-adjuster M , and conductor e , to the other pole of the battery. When the relay-lever l^2 leaves its front limiting-stop h —that is, when the line-circuit which includes the coils of the relay-magnet R' is opened and lever l^2 is withdrawn under the influence of its retractile spring rs toward its back stop i —the local circuit above traced is broken between lever l^2 and front stop h , and consequently momentarily the line-adjuster lever l falls away from its front contact b under the influence of its retractile y and

toward its back limiting-stop c , thereby opening or breaking the main-line circuit between lever l and the contact b ; but as soon as the sounder-lever l' reaches its back stop d a local circuit is established from local battery Lb , through conductor f , resistance r^3 , lever l' , stop d , conductor q , conductor n , the coils of magnet ac , and conductor e to the other pole of the local battery. Upon the completion of this circuit line-adjuster lever l returns to its front stop b , thereby closing the main-line circuit between said lever l and its contact or limiting stop b . When relay-lever l^2 returns to its closed position against its front stop h , a momentary division of the local circuit occurs, part passing from the point ji , through resistance r^3 , lever l' , stop d , conductor q , to point pi , and the other part passing from point ji , through conductor g , lever l^2 , stop h , the coils of sounder S , conductor k , to point pi , where the two circuits again unite and continue through conductor n and on to battery Lb through the coils ac and conductor e . The current traversing the last-traced circuit is sufficient to energize the core of sounder S to cause it to attract lever l' to closed position against its front stop d' . The breaking of contact between lever l' and its back stop d does not affect adjuster-magnet ac , because the current through it is maintained by contact between lever l^2 and its front limiting-stop h . The resistance r^3 should be as great or greater than the resistance of sounder S for best results.

If desired, a switch comprising the lever Sw and a coöperating contact-point z may be arranged in shunt around the lever l and its limiting-stops c and b , as clearly indicated in Figs. 2 and 5.

Fig. 4 shows a modification in which the local battery is divided into two parts, (designated, respectively, by reference-signs 1 and 2,) and when the relay-lever l^2 is closed both portions of the battery are coupled up in series and current therefrom flows through both the sounder and line-adjuster coils; but when the relay-lever l^2 and the sounder-lever l' are open and the latter is bearing against its back stop d the current through the line-adjuster coil ac is derived from part 1 only of the local battery, conductor f to lever l' , back stop d , conductor q , conductor n , magnet ac , and conductor e to return, and when the relay-lever l^2 returns to its closed position the core of sounder S is energized and attracts its lever l' to its front stop d' . As in the other forms of my invention above described, the breaking of contact between lever l' and its back stop d causes no movement of the line-adjuster lever l , because the current in magnet ac is maintained by the contact between relay-lever l^2 and its front stop h .

While I have described my invention as shown in Figs. 2 and 6 as employing two coils in connection with the line-adjuster mechanism and while I have shown in Figs. 3 and 4 the retracting-coil rc omitted and replaced by

a retractile spring y as a form embraced within the spirit and scope of my invention, it is obvious that other forms and arrangements embodying the same idea may also be equally well adapted for use in this connection. In practice, however, I prefer to employ the two coils ac and rc , for the reason that thereby I secure the advantage that when the coils are once adjusted so that the effect of the attracting-coil ac upon lever l bears the proper relation to the effect of the retracting-coil rc upon said lever thereafter any change in the strength of the local battery, whether diminishing or increasing, requires no new adjustment of the line-adjuster coils, because the current in them weakens or strengthens coincidently and to the same degree, and hence their relative effects on lever l remain the same. In the illustration of the modified constructions of Figs. 3 and 4 I have omitted the line-circuit. It will be understood, of course, that the line-circuit L remains the same in said figures as in Fig. 2.

In Fig. 2 I have shown the apparatus as applied to a terminal station—that is, where one pole of the main battery MB is connected to earth at E . It will be understood, of course, that where the apparatus is located at an intermediate station or office where there is no main battery the main line L instead of being connected through the main battery MB to earth E , as shown in Fig. 2, the line would extend on to the next office, as indicated by the dotted line L' , Fig. 2.

It may sometimes be desired to avoid completely breaking the main-line circuit at the line-adjuster lever l , but to greatly weaken said circuit by the removal of said lever l from its front stop b and to still retain a completed main-line circuit adequate at least to conduct impulses of current not intended to affect ordinary relays—such, for instance, as the impulses in telephonic or phonoplex transmissions. In order to accomplish this result, the break in the main-line circuit at the line-adjuster lever l may be shunted by a high resistance or by a condenser, or both. In Fig. 5 I have shown such shunt, in which is included both a high resistance r^4 and a condenser Cr . It will be understood, of course, that either the high resistance or the condenser may be omitted. It is also obvious that the shunt should be extended to include or to surround the key K and also might be extended to surround the main-line relay R' , as well as the line-adjuster lever l , as illustrated in dotted lines in Fig. 2.

Many variations and changes in the details of construction and arrangement of parts would readily occur to persons skilled in the art and still fall within the spirit and scope of my invention. I do not desire, therefore, to be limited or restricted to the exact details shown and described; but,

Having now set forth the object and nature of my invention and various constructions and arrangements embodying the principles

thereof, what I claim as new and useful and of my own invention, and desire to secure by Letters Patent, is—

1. In a telegraphic apparatus, a main-line circuit including a fixed contact, a vibrating lever coöperating therewith, devices for controlling the vibrating movements of said lever to open or close said main-line circuit, a relay, a sounder, and means actuated by said relay for operating said controlling devices, as and for the purpose set forth. 70

2. In an apparatus for avoiding the effects of leaks or escapes in telegraph-lines, the combination with the main line including a main battery, of a circuit-breaker interposed in the main line and intermediate the leak or escape and the battery and comprising a fixed contact and a vibrating lever arranged to coöperate therewith to open and close the main line, and means controlled by the opening of a key in the main line on one side of the leak or escape for rocking said lever to open the line connection with the main battery on the other side of the leak or escape, whereby all current is withdrawn from the line between said key and circuit-breaker, as and for the purpose set forth. 85

3. In an apparatus for avoiding the effects of leaks or escapes in telegraph-lines, a main line including a main battery, in combination with a vibrating lever, and a coöperating contact interposed in the main-line connection with said battery and between the battery and the leak or escape, means normally tending to hold said vibrating lever in closed relation with respect to its coöperating contact, and means actuated coincidently with the opening of a key in the main line on the opposite side of the leak or escape for rocking said lever out of coöperating relation with said contact momentarily to break the main-line connection with the battery, as and for the purpose set forth. 95

4. In an apparatus for avoiding the effects of leaks or escapes in telegraph-lines, a main-line connecting terminal or battery-stations, a circuit-breaking device interposed in the main line intermediate said line and its battery connection and comprising a fixed contact and a vibrating lever coöperating therewith, electrical devices operating to normally maintain said lever in closed relation with respect to said contact, means operating upon said lever and constantly tending to withdraw said lever from said contact, a local circuit for controlling said electrical devices, and means actuated by the opening of a key in said main line on the opposite side of the leak or escape for controlling said local circuit, as and for the purpose set forth. 115

5. In an apparatus of the class described, a main line, a main-battery connection therefor, a pivoted switch-lever and a coöperating fixed contact arranged in said main-battery connection, electrical devices for rocking said switch-lever toward and from said contact, a local circuit for said electrical devices, and

means controlled by the opening of a key at a distant transmitting-station for controlling the circuit of said electrical devices to momentarily open said switch-lever to break said 5 main-line connection with the main battery, as and for the purpose set forth.

6. In an apparatus of the class described, a main line, a battery connection therefor, a line-adjuster mechanism including a switch 10 arranged in said battery connection, magnets arranged to actuate said switch, one of said magnets tending to open the switch and the other to close the same, local circuits for said magnets, and means actuated by the 15 opening of said line-circuit at a distant transmitting-station for controlling the circuit of one of said magnets, as and for the purpose set forth.

7. In an apparatus of the class described, 20 a main line, a battery connection therefor, a fixed contact and a lever arranged in said battery connection, said lever coöperating with said fixed contact to make and break the connection of said battery to said main line, 25 an attracting-coil and a retracting-coil operating on said lever, local circuits for said coils, and means actuated by the opening of said line-circuit at a distant transmitting-station for controlling the circuit of said attracting- 30 coil, as and for the purpose set forth.

8. In an apparatus of the class described, a main line, a main-battery connection therefor, a switch-lever arranged in said connection, electrical devices for controlling said 35 switch-lever, a local battery, a sounder-circuit including said battery, said sounder-circuit having a branch which also includes said electrical devices, and a local relay for controlling said sounder-circuit, as and for the 40 purpose set forth.

9. In an apparatus of the class described, a main line, a main-battery connection therefor, a switch-lever arranged in said connection, an attracting-coil and a retracting-coil 45 for said lever, a local battery, a circuit for said retracting-coil including said battery, a

sounder, a circuit therefor including said local battery, said sounder-circuit having a branch including said attracting-coil, an auxiliary circuit for said attracting-coil, said 50 auxiliary circuit being controlled by said sounder, and a relay for controlling said sounder-circuit, as and for the purpose set forth.

10. In an apparatus of the class described, 55 a main line, a main battery connected thereto, a circuit-breaking lever arranged in said battery connection, an attracting-coil and a retracting-coil for actuating said lever, a local battery, circuit connections from said local battery for said retracting-coil, a sounder, a circuit for said sounder including said battery, said sounder-circuit having a branch including said attracting-coil, a relay arranged 60 in the main line for controlling said sounder-circuit and its branch, an auxiliary circuit for said attracting-coil, said auxiliary circuit being controlled by said sounder, and resistances arranged in said attracting and retracting coils circuits whereby the currents there- 70 in may be varied, as and for the purpose set forth.

11. In an apparatus for avoiding the effects of leaks or escapes in telegraph-lines, a main line including a main battery, a circuit-breaker interposed between said battery and main line, means actuated by the opening of a key in the main-line circuit at a distant transmitting-station for temporarily actuating said circuit-breaker to open said line-circuit to battery, a shunt around said circuit-breaker, and devices arranged in said shunt for diminishing the current to the main line when said circuit-breaker is open, as and for the purpose set forth. 75

In witness whereof I have hereunto set my hand, this 22d day of July, 1901, in the presence of the subscribing witnesses.
